UNITED STATES PATENT OFFICE.

JOHN HARRIES, OF NEW YORK N. Y.

DEVICE FOR RINSING AND WASHING GLASSES, TUMBLERS, AND THE LIKE.

1,186,313.

Specification of Letters Patent. Patented June 6, 1916.

Application filed April 2, 1915. Serial No. 18,734.

To all whom it may concern:

Be it known that I, JOHN HARRIES, a subject of the Emperor of Germany, and residing at New York, in the county of New York and State of New York, have invented certain new and useful Improvements in Devices for Rinsing and Washing Glasses, Tumblers, and the like, of which the following is a specification, such as will enable those skilled in the art to which it appertains to make and use the same.

This invention relates to devices for rinsing and washing glasses, tumblers, goblets, cups and the like, and the object thereof is to provide an improved device of this class particularly designed for use in bars, cafés, hotels and like places, but which may be used wherever such devices are required; and with this and other objects in view the invention consists in a device of the class specified, constructed and operated as hereinafter described and claimed.

The invention is fully disclosed in the following specification, of which the accompanying drawing forms a part, in which the separate parts of my improvement are designated by suitable reference characters in each of the views, and in which:

Figure 1 is a sectional side view of a device of the class specified and indicating the method of its use; and, Fig. 2 a cross section on the line 2—2 of Fig. 1.

In the practice of my invention, I provide a device of the class specified, comprising a base *a* having a central tubular standard *b* in the top of which is secured a block *c* through which is passed a spirally formed, or spirally grooved shaft *d*, and mounted on the tubular standard *b* and the shaft *d* is a spiral spring *e* which normally projects to a distance above the tubular standard *b* approximately the same as the height of said standard and the length of the shaft *d* is preferably about one inch greater than that of the standard *b*, including the base *a*.

Loosely mounted on the shaft *d* is a block *f* in which said shaft is rotatable, and the lower end of the spring *e* has a bearing at the bottom of the standard *b* and the upper end thereof bears on the block *f*, and the end of said standard above said block is screw-threaded and provided with two nuts *g* and *g*², and a washer *g*³ is preferably placed between the lower nut *g* and the block *f*, and between the nuts *g* and *g*² is secured a yoke-shaped or U-shaped spring *h*, the side arms

of which extend downwardly, and I also provide a brush *i* comprising a cup-shaped body *i*² the inner walls of which are approximately parallel and the outer walls of which are covered with, or provided with brush material *i*³, and the inner walls of the body *i*² of the brush *i* are preferably provided with longitudinal grooves *i*⁴ in which the side arms of the spring *h* fit when the brush or brush body is passed down over the spring *h*, and the top of the shaft *d* and the parts connected therewith including the upper end portion of the spiral spring *e* as shown in Fig. 1, and said spring serves to hold the brush *i* and cause it to rotate with the shaft *d* in the operation of the device, as herein-after described. The lower end portion of the shaft *d* is also provided with a stop pin *j* which limits the upward movement of said shaft in the operation of the device, as herein-after described, and the length of the shaft *d* is preferably such that when in its lowest position the lower end thereof will project below the bottom of the base *a*, and in this position the stop pin *j* may be inserted as will be readily understood and detached for the purpose of disconnecting the separate parts of the device.

In the use of this device it is set in a tank, sink, tub or other suitable vessel containing water, and a goblet, glass, tumbler or other device *k* to be cleaned is passed down over the brush *i* and by means of the glass, tumbler or other device the brush *i* and shaft *d* are forced downwardly by hand into the position shown in dotted lines in Fig. 1, and in this operation the shaft *d* and brush *i* are rapidly rotated and at the limit of the downward movement the pressure is removed, while the glass, goblet, tumbler or other device is still held in the hand and the spring *e* forces the brush upwardly and with it the glass, goblet or other device and the brush is rapidly rotated in the opposite direction and the interior of the glass, goblet, tumbler or other device is thus thoroughly cleaned.

My invention is not limited to the idea of washing the inner side of the glass only, as herein shown and described, and means may be provided for washing or cleansing the outer side thereof at the same time as in other devices of this class, and of which this is an improvement.

By placing the spring *e* on the outer side of the standard *d* and providing the brush *i*

of the form and construction herein shown and described, the necessary height of the device is limited to such an extent that it can be used in tanks, sinks and other receptacles of much less depth than has heretofore been possible with devices of this class, and it must be understood that the exact form of the brush *i* herein shown and described need not necessarily be employed, 10 the only essential feature in this connection being, that the body of the brush be provided with a cup-shaped or other recess to receive the spring *h*, as herein shown and described, and that the said brush body 15 when in its lowest position will inclose the standard *b*, or the top portion thereof.

Having fully described my invention, what I claim as new and desire to secure by Letters Patent, is:—

20 1. A washing device of the class described, comprising a base having a tubular standard the top of which is provided with a block through which is passed a spirally grooved and vertically movable and rotatable shaft, a spiral spring inclosing the standard and said shaft and having a bearing at the bottom of the standard and at the top of the shaft, a yoke-shaped spring 25 secured to the top of the shaft and the side arms of which extend downwardly, and a brush comprising a body portion having a cup-shaped recess and adapted to be passed downwardly over said shaft and said spring, and the inner 30 side walls of which are provided with vertical grooves to receive the side arms of said spring.

cup-shaped recess and adapted to be passed downwardly over said shaft and said spring, and means for preventing the rotation of the brush on said spring.

2. A washing device of the class described, comprising a base having a central tubular standard the top of which is provided with a block through which is passed a spirally grooved and vertically movable 40 and rotatable shaft, a spiral spring inclosing the standard and said shaft and having a bearing at the bottom of the standard and at the top of said shaft, a yoke-shaped spring secured to the top of said 45 shaft and the side arms of which extend downwardly, and a brush comprising a body portion having a cup-shaped recess and adapted to be passed downwardly over said shaft and said spring, and the inner 50 side walls of which are provided with vertical grooves to receive the side arms of said spring.

In testimony that I claim the foregoing as my invention I have signed my name in 55 presence of the subscribing witnesses this 1st day of April, 1915.

JOHN HARRIES.
